US0D1042960S

(12) United States Design Patent (10) Patent No.: US D1,042,960 S
(45) Date of Patent: * Sep. 17, 2024

(54) COMB FOR A HAIR REMOVAL DEVICE

(71) Applicant: Braun GmbH, Kronberg (DE)

(72) Inventors: Rüdiger Boss, Frankfurt (DE); Björn Kling, Glashütten (DE); Lingxuan Kong, Frankfurt (DE); Wolfgang Stegmann, Frankfurt (DE)

(73) Assignee: Braun GMBH, Kronberg (DE)

() Term: 15 Years

(21) Appl. No.: 29/852,245

(22) Filed: Sep. 6, 2022

Related U.S. Application Data

(62) Division of application No. 29/728,386, filed on Mar. 18, 2020, now Pat. No. Des. 967,535.

(57) CLAIM

The ornamental design for a comb for a hair removal device, as shown and described.

DESCRIPTION

FIG. 1 is a perspective view of a comb for a hair removal device;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

1 Claim, 7 Drawing Sheets
